UNITED STATES PATENT OFFICE

2,207,209

DESK CALENDAR

Martin E. Trolen, St. Paul, Minn., assignor to
 Brown & Bigelow, St. Paul, Minn., a corpora-
 tion of Minnesota

Application April 28, 1937, Serial No. 139,564

9 Claims. (Cl. 40—115)

My invention relates to an improvement in cal-
 endars of a type designed to simulate a steering
 wheel of a ship, and which may be easily ad-
 justed to change the date from day to day. The
 5 calendar is of the perpetual type which may be
 used from one year to another.

It is the purpose of my invention to provide a
 calendar of attractive design which may be po-
 sitioned on a desk or table to indicate the date.
 10 Each day the calendar is operated to change
 the indication and to display another date.

An object of my invention is to provide a
 calendar operable to display each date in rela-
 tively large size without providing a rotor of
 15 large diameter. It is a comparatively simple
 matter to construct a calendar having a single
 rotatable member which is concealed behind a
 masking plate which permits but one date to be
 displayed at a time. For actual use, however,
 20 the rotatable disc bearing the 31 possible days
 in a month must be of large diameter to provide
 an indication which may be seen from any dis-
 tance. If the rotor is sufficiently small to pro-
 vide a pleasing appearance when placed upon a
 25 desk or table, the figures on such a single disc
 are too small to be easily seen.

My invention embodies two separate discs, one
 of which carries indicia for displaying the first
 number of each number over 9 and provides an
 30 opening through which a portion of a second disc
 may be displayed. The second disc bears the
 first 9 numbers and acts to form the second num-
 ber of the dates indicated above 9. By utilizing
 two superimposed discs and providing openings
 35 through the first disc through which portions of
 the second disc may be visible, I am able to pro-
 vide a calendar which requires a maximum of 10
 single numerals arranged about the same. Ob-
 viously, these numerals can be approximately
 40 several times the size which they would be on the
 same size disc if 31 separate dates were formed
 thereon. It is obvious that when all of the num-
 bers are formed on a single disc, 22 of the 31 num-
 bers necessary are comprised of two digits mak-
 45 ing the total of 53 digits necessary in place of 10
 in my construction.

My calendar embodies a cam arrangement
 which operates to rotate each disc when necessary
 and to permit one disc to remain stationary for a
 50 desired period of time. By this means, I am able
 to move the discs to indicate successive numbers
 from 1 to 31 whereupon the device will automatic-
 ally start numbering the first of the next
 month.

55 These and other objects and novel features of

my invention will be more clearly and fully set
 forth in the following specification and claims.

In the drawings forming a part of my speci-
 fication:

Figure 1 is a front elevation view of my cal- 5
 endar.

Figure 2 is a vertical section centrally through
 the calendar on the line 2—2 of Figure 1.

Figure 3 is a front elevation view of the upper
 portion of the calendar supporting standard, with 10
 the rotatable members removed therefrom.

Figure 4 is a front elevation view of a ratchet
 arrangement acting to provide an audible click as
 the rotating portion moves from one indicating
 position into another. 15

Figure 5 is a side elevation view of the ratchet
 member illustrated in Figure 4.

Figure 6 is a rear view of the rotating wheel
 mounted upon the standard of Figure 3.

Figure 7 is a locking key for holding the wheel 20
 in place upon the standard.

Figure 8 is a front elevation view of the ro-
 tating wheel in place upon the standard, the
 indicating mechanism being removed there- 25
 from.

Figure 9 is an elevation view of one indicating
 disc of my calendar.

Figure 10 is an elevation view of the other in-
 dicating disc of my calendar.

Figure 11 is an elevation view of the cam by 30
 means of which the calendar is actuated.

Figure 12 is a front elevation view of my
 calendar with the front masking plate removed,
 illustrating the indicating discs in one position.

Figure 13 is a view similar to Figure 12, show- 35
 ing the indicating discs in another position.

My calendar A is mounted upon a base 10
 having an aperture 11 in the front thereof
 through which a rotatable disc 12 may be ob-
 served. The disc 12 is provided with a pivot 13 40
 extending through the bottom 14 of the cal-
 endar A. The bottom 14 is provided with a cir-
 cumferential flange 15 which is pressed within
 the vertical wall 16 of the base 10. The disc 12
 is inclined downwardly to some extent at 17 to 45
 extend parallel to the inner sloping wall 19 of
 the base 10. The pivot 13 terminates in a knob
 20 which extends below the bottom 14 and which
 may be engaged by the fingers to rotate the
 disc 12. 50

The base 10 extends upwardly terminating in
 a circular plate portion 21 having an axis at a
 slight angle with the horizontal. The plate por-
 tion 21 comprises an annular flange 22 and a cen-
 tral square shank 23 extending axially from the 55

surface thereof. A circular shoulder 24 extends slightly forward from the service of the plate portion 21, and between this shoulder 24 and the annular flange 22, I provide a series of radially extending notches 25 forming a ratchet.

The rotatable member mounted upon the shank 23 is designed to simulate a ship's wheel. This wheel 26 is provided with a series of radially extending spokes 27 spaced at intervals about the periphery thereof, by means of which the wheel 26 may be rotated. The rear surface 29 of the wheel 26 is provided with a series of ratchet teeth 30 arranged in a circle, which teeth are similar to and of equal diameter to the ratchet teeth 25 in the standard 10. Interposed between the teeth 25 and 30, I provide a disc 31 having a pair of spring ratchet fingers 32 and 33 cut from the body thereof as illustrated in Figures 4 and 5. The finger 32 engages the ratchet teeth or notches 30 on the wheel 26. The fingers 32 and 33 permit the wheel to rotate in either direction and provide an audible click each time the wheel passes through a predetermined angular distance necessary to change the calendar from one indication to another.

The wheel 26 is provided with a central opening 34 of just sufficient size to fit over the shoulder 24 on the standard 10 as illustrated in Figure 2 of the drawings. The wheel 26 may thus rotate freely with respect to the standard and each time the wheel rotates through a certain predetermined angularity, a click is heard indicating that the calendar is in indicating position. In the modification shown, the circle is divided into 11 parts, and each time the wheel is turned $\frac{1}{11}$ of a rotation, a click is heard. The wheel 26 is held in position by means of a locking key 35 which engages in a slot extending partially around the square shank 26 on the inside of the wheel. The locking key 35 engages against the inner surface of the wheel 26, holding this wheel in proper position upon the shoulder 24.

An indicating disc 36 is rotatably mounted upon the square shank 23 adjacent the locking key 35. The disc 36 illustrated in Figure 9, is provided with a circular opening 37 in the center thereof, to permit the rotation of this disc upon the square shaft. A pin 39 extends outwardly from the inner surface of the wheel 26, and engages in a notch 40 in the periphery of the disc 36. The pin 39 is just sufficiently long to engage the disc 36 without interfering with the operation of the outer indicating disc which will be later described. Engagement of the pin 39 in the slot 40, causes the disc 36 to rotate with the wheel 26 at all times, so that every time the wheel 26 is turned, the disc 36 also turns the same distance.

The outer indicating disc 41 illustrated in Figure 10 of the drawings, is supported on the shank 23 and is held in spaced relation with the disc 36 by a pair of spacing washers 42. The disc 41 like the disc 36 is provided with a central circular opening 43 so that this disc may also rotate upon the square shank 23. The disc 41, however, only rotates at intervals as will be described. The outer periphery of the disc 41 is provided with a series of notches 44 and also with a notch 45. The major portion of the periphery of the disc 41 is at a constant radius from the center of the disc. On either side of the notch 45, however, is a portion extending beyond the radius of the remainder of the disc. These portions of greater radius are designated as 46 and 47.

Four openings are provided through the disc

41. Adjacent one opening 49, the disc is entirely blank and without any indicia. Adjacent a second opening 50, I provide a numeral 1 indicated at 51. Adjacent a third opening 52, I provide a numeral 2 designated at 53. Adjacent the fourth opening 54, I provide a numeral 3 designated at 55. Between the openings 49 and 54, I provide the numerals 31 indicated at 56.

Externally of the disc 41, I provide a locking key 57 similar to the locking key 35 illustrated in Figure 7. This locking key 57 extends in a slot in the square shank 23 and holds the discs 36 and 41 and the various spacing washers in proper relative position on the shank.

On the shank 23 adjacent the locking key 57, I provide a cam 59. The cam 59 is provided with a section 60 which in the present case equals $\frac{2}{11}$ of the distance about the cam. A notch 61 slightly deeper than the section 60 and separated therefrom by a slight hump 62, is provided at one end of the section 60. A second section 63 of slightly greater radius than the section 60 and equal in length to $\frac{3}{11}$ of the distance about the circumference of the cam, is provided adjacent the section 60 and connected therewith by a slight incline 64. The remaining $\frac{6}{11}$ of the cam is of constant radius which is slightly greater than the radius of the section 63. This last named section is designated 65 on the drawings. The cam 59 is provided with a square central opening to fit about the shank 23, to prevent rotation of the cam 59. An opening 67 in the cam 59 permits portions of the discs 36 and 41 to be viewed therethrough.

A masking plate 69 illustrated only in Figures 1 and 2 of the drawings, completes the assembly. The masking plate 69 fits closely within the rim 70 of the wheel 26 and conceals the inner mechanism. The masking plate 69 is provided with a square central opening 71 to fit the shank 23, and is held from rotation with respect to the shank and standard. Two spaced openings 72 are provided in the masking plate 69 which openings register with the opening 67 in the cam 59 to provide a view of the indicating discs 41 and 36. The masking plate 69 is held in place by a washer 73 and the bolt 74 which is threaded into the square shank 23.

A flat spring 75 is secured by rivets 76 or other suitable means within the wheel 26. This spring 75 is provided with a rounded end 77 which provides a means of rotating the disc 41 at intervals.

In the operation of my device, we will start with the calendar in the position illustrated in Figure 1 of the drawings, with the numeral 1 being displayed through the masking plate 69. This numeral 1 is the numeral on the disc 36 and is seen through the opening 49, through the opening 67 in the cam 59, and through one of the openings 72. As the opening 49 is provided with a blank surface adjacent the same, no numeral will be indicated through the other opening 72 in the masking plate 69.

Upon the second day of the month, one of the handles or spokes 27 is engaged, and the wheel 26 is rotated through $\frac{1}{11}$ of a rotation. This action also rotates the disc 36 through $\frac{1}{11}$ rotation causing the numeral 2 indicated on the disc 36 to appear through the opening 49 in place of the numeral 1. During this time, the spring 75 is in the approximate position illustrated in Figure 13, the rounded end 77 thereof engaging the portion 63 of the cam. While the spring 75 is sufficiently wide to engage both the cam 59 and the disc 41 at the same time, the section 63 is of slightly

greater diameter than the major portion of the disc 41, and accordingly the disc 41 will not be rotated.

The wheel 26 may be rotated for the first eight days of the month without actuating the disc 41 in any way. During this time, the spring 75 will slide over the section 63 of the cam 59, and then over $\frac{5}{6}$ of the section 65 of the cam. Upon turning the wheel 26 to indicate the ninth day 10 of the month, the spring 75 slides over the remaining $\frac{1}{6}$ of the section 65 and drops into the section 69 of the cam 59. As this section 69 is of smaller radius than the disc 41, the rounded end 77 of the spring 75 will drop into a notch 15 44 in this disc 41. In turning the wheel 26 to cause indication of the numeral 10, the spring 76 engaged in a notch 44 will cause rotation of the disc 41 as well as the disc 36. In turning from the numeral 9 to display of the numeral 10, 20 it is necessary to rotate the wheel 26 through $\frac{2}{11}$ of a rotation which brings the opening 50 in registry with one of the openings 72, while the numeral 1 on the disc 41 designated at 51 in the drawings, will be in registry with the other opening 72. It will be found that further rotation 25 of the wheel 26 will cause the spring 75 to engage the inclined portion 64 of the cam 59, disengaging the end 77 of the spring 75 from the notch 44 and permitting the rotation of the wheel 26 through the remaining $\frac{1}{11}$ of a rotation without engaging the disc 41 to further rotate the same. The position of the spring 75 when the calendar is displaying the eleventh day of the month is illustrated in Figure 13.

Upon the nineteenth day of the month, the calendar is rotated through the last portion of its engagement with the section 65 of the cam 59, and the end 77 of the spring 75 will engage in the next succeeding notch 44. In turning the 30 calendar from indication of the nineteenth day to the twentieth day of the month, the wheel 26 must again be rotated through $\frac{2}{11}$ of a rotation while the spring 75 engages in the notch 44. This moves the opening 52 into registry with one 35 of the openings 72, while the numeral 2 indicated at 53 is visible through the other opening 72. The disc 36 is simultaneously rotated so that the zero appearing thereon is visible through the opening 52. Further rotation of the wheel 26 causes the end 72 of the spring 75 to engage the inclined portion 64 of the cam 59, disengaging the spring from the notch 44 and permitting the remaining $\frac{1}{11}$ of the rotation to indicate successive numbers through the opening 52 without changing the position of the disc 41.

Upon the twenty-ninth day of the month, the end 77 of the spring 75 engages in the notch 45 of the disc 41. In changing to the thirtieth day of the month, it is necessary to rotate the wheel 26 through $\frac{2}{11}$ of a rotation. This movement causes rotation of the disc 41 together with the disc 36, and moves the opening 54 into registry with one of the openings 72, and the numeral 3 indicated at 55 into registry with the other of the openings 72. The numeral zero indicated on the disc 36, will appear through the opening 54 so that the date 30 will be displayed through the masking plate 69. Continued movement of the wheel 26 to cause display of the numeral 31, 50 causes the end 77 of the spring 75 to engage the incline 64 and to ride along the cam through the section 63. It will be remembered, however, that adjacent the notch 45, the disc 41 is of greater radius than throughout the remainder of the disc. Accordingly, the movement of the

spring end 77 on to the section 63 of the cam does not disengage the spring from the notch 45. Accordingly, continued movement of the wheel 26 through the next $\frac{3}{11}$ of a rotation acts to move the numerals 31 indicated at 56, the registry with the opening 67 in the cam 59 and with the opening 72 of the masking plate 69.

The complete month has in this way been indicated. In order to reset the calendar to display the first day of the month, once again it is necessary to rotate the wheel 26 through $\frac{6}{11}$ of a rotation, while the spring 75 rides upon the section 65 of the cam during which time the disc 41 does not rotate. At the end of $\frac{6}{11}$ of a rotation, the spring 75 engages a notch 44 in the disc 41, and during the next $\frac{1}{11}$ rotation, the disc 41 is rotated so that the opening 49 moves into registry with one of the openings 72 and the numeral zero on the disc 36 appears through the opening 49. Further rotation of the wheel 26 through $\frac{1}{11}$ of a revolution, disengages the spring 75 from the notch 44 and moves the numeral 1 on the disc 36 into registry with the opening 49 on the disc 41. The calendar is then in readiness for the next month. At the first of each month, the knob 28 is engaged by the fingers and rotated $\frac{1}{2}$ of a revolution as the names of the various months are indicated on the disc 12, movement of this disc will move the name of the next succeeding month into registry with the display opening 17 and the standard 10.

In accordance with the patent statutes, I have described the principles of operation of my calendar, and while I have endeavored to set forth the best embodiment thereof, I desire to have it understood that this is only illustrative of a means of carrying out my invention and that obvious changes may be made within the scope of the following claims without departing from the spirit of my invention.

I claim:

1. A calendar comprising a standard, a wheel rotatable upon said standard forming a calendar body, rotatable disc means on said standard within said wheel rotatable relative to said wheel, but actuated by movement of said wheel, and masking plate means within said wheel and held stationary by said standard, said plate having an aperture therein through which a portion of said disc means is displayed.

2. A calendar comprising a standard, a rotatable wheel thereon forming a calendar body and having a recess therein, rotatable disc means on said standard within said wheel rotatable relative to said wheel, but actuated by rotation of said wheel to rotate, a masking closure for said wheel recess having an aperture therein through which a portion of said disc means is displayed, means supporting said closure non-rotatably on said standard, and indicia on said disc means visible through said aperture.

3. A calendar comprising a base, a rotatable wheel thereupon, a plurality of relatively rotatable disc means bearing angularly spaced calendar indicia mounted on said base within said wheel, means operable with said wheel to rotate said disc means by rotation of said wheel, aperture means in the outermost of said discs through which the innermost disc may be viewed, and stationary masking means secured to said base and extending over said disc means within said wheel displaying a selected portion of said disc means.

4. A calendar comprising a base, a wheel rotatable upon said base, a disc rotatably supported

within said wheel and rotatable together with said wheel, a second disc having angularly spaced openings therethrough rotatably supported concentrically with said first disc, means on said wheel for rotating said second disc through a predetermined angularity with said wheel during each rotation of said wheel.

5. A calendar comprising a base, a hollow wheel rotatable on said base, a masking plate having an opening therethrough supported non-rotatably on said base positioned to act as a closure for said hollow wheel, a disc within said wheel rotatable with said wheel, a second disc having angularly spaced openings therethrough rotatably mounted within said wheel between said first disc and said masking plate, means within said wheel engaging said second disc during a portion of each rotation of said wheel to move said second disc from one position where one 10 opening through said second disc registers with the opening in said masking plate to another position where another opening in said second disc registers with said masking plate opening.

15. A calendar comprising a base, a wheel having a recess in one side thereof rotatably supported on said base, a disc bearing numerals from zero to nine angularly spaced thereon, a second disc bearing angularly spaced numerals from one to three thereon, said numerals each having an opening through said second disc adjacent the same through which a numeral on said first disc may be displayed, said second disc having also an opening therethrough adjacent a blank portion thereof, a masking plate closing said wheel 20 recess containing a recess through which a portion of said discs may be displayed, and means for rotating said second disc with said wheel during a portion of the rotation thereof, permitting the numerals zero through nine on said first disc to be displayed through said masking plate opening and said last named opening in said second disc, said numerals zero through nine to be subsequently displayed through the opening in said second disc adjacent the numeral one 25 on said second disc to display numbers ten through nineteen by rotation of said wheel, and to similarly display subsequent numbers indicating days of the month through continued rotation of said wheel.

7. A calendar comprising a base, a wheel having a concentric recess in one side thereof rotatable on said base, means in said wheel and rotatable therewith having angularly spaced numerals thereon, a second disc rotatable with relation to said wheel mounted within said wheel having openings therethrough through which a portion of said numerals may be displayed, numerals on said second disc adjacent some of said openings providing indicia cooperable with the indicia on said first disc, and means on said wheel engageable with said second disc to rotate the same a predetermined amount during each rotation of said wheel, and a masking plate covering said recess having an aperture through which a portion of said discs may be displayed, rotation of said wheel causing indication through the masking plate openings of numerals one through thirty-one.

8. A calendar comprising a base, a rotatable member having a recess in one side thereof on said base, a disc bearing a set of angularly spaced numerals arranged within said recess and rotatable therewith, a second disc having angularly spaced openings therethrough within said recess, 25 cam means mounted in said recess adjacent said second disc, means on said rotatable member engageable with and rotatable over said cam, and controlled by said cam to contact with said second disc for a certain period of rotation of said member to rotate said second disc at intervals.

9. A calendar including a base, a member rotatably mounted thereon having a recess therein, a masking plate closing said recess and having a sight aperture therein, means bearing angularly spaced numerals in said recess rotatable with said member to be consecutively displayed through said aperture, a disc rotatable in said aperture and covering said numerals, spaced openings in said disc through which said numerals may be seen, indicia adjacent some of said openings cooperable with said numerals, a cam stationarily mounted in said recess, and means on and rotatable with said member engaging said cam and controlled thereby to move said disc 40 with said member during a predetermined angular distance during each revolution of said member.

MARTIN E. TROLLEN.
